UNITED STATES PATENT OFFICE.

ALBERT H. BATES, OF CLEVELAND, OHIO.

STREET-CAR.

No. 861,700.

Specification of Letters Patent.

Patented July 30, 1907.

Application filed September 12, 1903. Serial No. 173,004.

To all whom it may concern:

Be it known that ALBERT H. BATES, a citizen of the United States, residing at Cleveland, in the county of Cuyahoga and State of Ohio, have invented a certain 5 new and useful Improvement in Street-Cars, of which the following is a full, clear, and exact description, reference being had to the accompanying drawings.

Open street cars with transverse seats extending the full width of the car, and a running board along one side 10 of the car are very popular with both the management and the public,—with the former on account of their large carrying capacity and speed of unloading, and with the latter because of their coolness and ventilation. They have many drawbacks however. First, from the 15 company's standpoint there is the delay in loading after the car has become reasonably full. This is especially noticeable when the car stops for a lady passenger. She must select, before she boards the car, the particular seat she is to occupy. If the nearest seat is full she 20 walks along the ground to the next, and then to the next and so on, frequently walking the whole length of the car before boarding it. If the seats are all occupied the delay is still greater for then she is liable to wander back and forth several times in the endeavor to 25 select the seat in which the men look most amiable and most liable to give up their seats, or at least in an attempt to avoid those seats where men are sitting who are fresh from some factory and whose garments would be liable to soil her gown. This delay occurring at 30 frequent stops in the run aggregates a very considerable amount. During a rain storm the delay is still greater, for then the side curtains are down and the passenger must raise a curtain, and if that compartment is occupied she holds the car until she has tried another, and 35 so on. The aggregate delay in the running schedule caused by these frequently occurring delays in loading reduces the number of car miles per hour, and it therefore requires a larger number of cars to accomplish the same transportation. From the standpoint of the 40 conductor, the present system of cars with transverse seats entirely across the car is objectionable in that there is danger of his being knocked or thrown from the running board while collecting fares, by contacting with a vehicle on the street. It is difficult for him to collect the 45 fares and give transfers to the passengers at the extreme inner ends of the seats, and during a rain storm he may get very wet while performing this duty. These disadvantages have been so great that some of the street 50 railway unions have demanded that an aisle be cut through the car for the benefit of the conductor. Finally, there are in the present style of cars above referred to, disadvantages to the passengers,—and even the passengers have some rights which should be respected. Thus it is extremely disagreeable for the 55 passengers to be continuously climbing over each other to get in or out. It is annoying particularly to a lady to

have no means of rearranging her seat when the car is in motion, as, for example, when she has been unfortunate enough to obtain a seat next to a man who has too recently visited a saloon. Moreover after the car 60 has been crowded and passengers standing in some of the compartments, there will be vacancies in other parts of the car which the standing passengers cannot reach. Finally in a rain storm the condition of the passengers is disagreeable in the extreme; the rain spatters in around the curtains; curtains being down, passengers cannot see out to tell where they are, and when they come to get out the drippings from the raised curtain fall on their garments or the backs of their necks. To overcome many of these disadvantages, cars are 65 frequently made with an aisle through the center, there being a seat on each side for accommodating two persons. This, however, reduces the carrying capacity of the car about 20 per cent, and this method is not adapted in most places. 70

I have discovered that all the disadvantages can be overcome without materially reducing the seating capacity of the car, by forming a longitudinal aisle in the car near its inner side and placing one longitudinal seat, or row of seats, against the inner side and forming 80 other seats crosswise to the outer edge. This makes one longitudinal aisle near the inner side of the car and numerous cross aisles, between the cross seats, extending thereto from the running board. This allows the space opposite the inner ends of the cross aisles to be 85 used for seats,—these seats taking the place of the space which would be so used in an ordinary transverse seat, but has here been made into an aisle. The advantages of such a car are that the passengers may readjust themselves while the car is in motion so that a passenger 90 may board the car without waiting to select an unoccupied seat. There will not be the disagreeable feature of crawling over each other in getting out for there are two exits for every cross seat, one by means of the running board directly and the other from the 95 other end of the seat through the longitudinal aisle. When the car is crowded one definite place may be reserved for passengers entering, allowing them to take seats after the car has started. During a rain storm all the curtains may be continuously kept down, the passengers entering from the rear platform by means of the 100 internal aisle. The conductor may collect his fares from the internal aisle.

My invention comprises a car thus arranged, comprehending broadly a longitudinal aisle nearer one side 105 than the other, cross seats extending from the aisle to the outer side of the car and seats in a longitudinal row between the aisle and the inner side of the car and opposite the cross aisles between the cross seats.

The invention may also be summarized as consisting 110 of a car constructed and arranged as herein shown and described and as definitely set out in the claims.

In the drawings, Figure 1 is a side elevation of my improved street car; Fig. 2 is a horizontal section of the same showing the arrangement of seats; Fig. 3 is a side elevation of the car from the side opposite Fig. 1; Fig. 5 4 is a horizontal section showing another method of arranging the longitudinal seats.

Referring to the parts by letters, A represents the central or body portion of the car; A¹, A² the front and rear platforms thereof.

10 B represents the steps or running board of the car located usually along the right hand side. On this side the car is open, the roof D being carried by vertical posts E as usual. The left hand side of the car however is preferably of the closed pattern having longitudinal panels F and above those, windows F' which are adapted to be closed, or lowered to be open as usual in street cars of the box type. The car thus provided is right handed only, but such form is much better than the older style having a running board on each side, on 15 account of the extreme danger following egress on the left hand side, and many street railroads are using nothing but right handed cars.

The transverse seats in my car are designated G. They extend crosswise of the car from the posts E, 25 about three-fifths of the way across the car. Opposite the inner ends of these seats is a longitudinal aisle a connecting at one or both ends with the platforms. Suitable sliding doors as H, H' are shown as provided opposite the ends of this aisle. Between the aisle a 30 and the inner side of the car is a single longitudinal row of seats either in the form of one long bench J as shown in Figs. 1 and 2, or individual chairs J' as shown in Fig. 4. If chairs are used they are turned somewhat diagonally so that the feet of one passenger extends beneath 35 the chair in front of him.

Whether the individual chairs are used or the long bench, there is, in either event, a single longitudinal row of seats provided thereby between the longitudinal aisle and the closed side of the car, and in this row passengers sit not only opposite the ends of the transverse seats G, but opposite the ends of the transverse aisles a' 40 between these seats.

Transverse seats when extending clear across the car usually accommodate five persons. In my car these 45 seats will accommodate three persons, another person would sit on one of the longitudinal seats directly opposite the transverse seat, and still another in the space opposite the aisle just behind the transverse seat. These passengers who sit opposite the transverse 50 aisles thus take the place of those who would sit on the cut out portion of the transverse seat. There being one less transverse aisle than seats, there would be a loss by this arrangement of seating space for one passenger. This loss, however, is immaterial. Moreover 55 in the form shown in Fig. 2 it would be overcome by the passengers sitting a trifle closer on the long through bench J.

I deem it advisable to leave an extra wide transverse aisle a² at the center of the car for a general entrance 60 and exit. The seating space which is lost by making this extra wide aisle is compensated for however, because the transverse seats accommodating but three people instead of five can be placed closer together, since the amount of crossing over each other which the 65 passengers have to do is very much reduced. Instead

of there being a passenger at the inner end of the complete transverse seat who would have to cross four sitting passengers to get out, it is only the intermediate passenger of the three on my cross seats who has to do any crossing and he need cross only one passenger, the 70 one at each end of the seat, and that passenger has room to turn slightly endwise of the seat to allow the passage. I compute that the saving in width of the cross aisles a' thus accomplished will allow for the extra wide center aisle a² without diminishing the number of seats from 75 what they would be if they extended the full width of the car. The extra space heretofore provided in the cross aisles is to allow the passengers to pass each other with more or less convenience, but it is unnecessary for comfort in sitting, as there is space under each seat for the 80 feet of the passenger on the seat just behind.

The car constructed as above described has therefore substantially the same seating capacity as one of the ordinary type where the seats extend clear across. The available space for standing room in case of emergencies 85 is probably as great or greater and certainly much more satisfactory; for the longitudinal aisle a and the main cross aisle a² may be used for this purpose, being much more convenient for the standing passengers than where they stand within the cross aisles and not 90 nearly so annoying to the seated passengers.

With the windows on the left hand side of my car lowered, the coolness and ventilation is substantially the same as with the ordinary car referred to. In case of a rain storm these windows may be raised and the 95 curtains on the opposite side drawn entirely to the floor. The car would thereby be practically as dry as a box car and passengers would be able to see out through the windows, the entrance and exit being at such a time confined to the main cross aisle a² or by way 100 of the rear platform. The amount of rain which will get into the car would be minimized as would also the delay in loading. K represents the rolled up curtains which may be of any suitable form such as are now common in open cars. They are, however, preferably of such length that they may be drawn down entirely to the floor. In case of a severe storm or if it should suddenly become cold all the side curtains may be kept down and entrance and egress to and from 105 the car provided by the rear door H and the rear platform. 110

It will thus be seen that my car has all the advantages of the open car with the continuous cross seats, and the open car with a central aisle, without the disadvantages of either type, while my car has in addition 115 many advantages peculiar to itself, particularly in its immunity from the disagreeable effects of wet weather.

I claim:

1. In a street car, a longitudinal aisle nearer one side than the other, longitudinal seating means between said aisle and the near side of the car and transverse seats between said aisle and the far side of the car, said longitudinal seating means having seats opposite the spaces between the transverse seats. 120
2. In a street car open at one side, a longitudinal aisle nearer the other side, transverse seats between said aisle and the open side and longitudinal seating means between said aisle and the other side. 125
3. A street car having an open side, transverse seats extending therefrom part way across the car, a longitudinal aisle within the car nearer the other side thereof opposite the ends of said seats, and a cross aisle from said longitudinal 130

- dinal aisle to the open side of the car, said cross aisle being wider than the aisle-space between consecutive transverse seats. 60
4. A street car open at one side and closed at the other 5 and having cross seats extending from the open side substantially three-fifths of the width, longitudinal seating means at the closed side occupying substantially a fifth of the width and an intermediate longitudinal aisle occupying substantially a fifth of the width. 65
- 10 5. In a convertible car, a permanently closed side, seating means extending longitudinally along said closed side, a longitudinal aisle directly in front of the same and nearer said permanently closed side than the other side, transversely disposed seats extending from the aisle to 70 said other side of the car, and means for closing the last mentioned side of the car. 70
- 15 6. In a convertible car having a permanently closed side, a running board along the opposite side of the car, longitudinally extending seating means within the car upon the closed side, a longitudinally disposed aisle in front of the same, transversely disposed seats extending from the aisle to the other side of the car, and means for closing the openings in the side of the car between the transverse seats. 80
- 20 7. The combination of a car having one permanently closed side, the opposite side being adapted to be open, seating means extending along such permanently closed side and nearer said permanently closed side than the opposite side and adapted to seat a single longitudinal row of passengers, a longitudinal aisle in front of such seating 85 means, and short permanent cross seats extending from said aisle to the opposite side of the car. 85
- 25 8. In a car, the combination of a permanently closed side, means for seating passengers in a row with their backs to said side, a longitudinal aisle which said passengers face, and cross seats extending from said aisle to the open side of the car and adapted to carry passengers facing forward, said closed aisle being nearer the longitudinal side of the car than the open side, and there being a doorway at the rear end of said aisle. 90
- 30 9. A car having one side permanently closed, seating means extending longitudinally along such side and facing toward the opposite side, the opposite side of the car having vertical posts between which there are adapted to be open spaces and permanent cross seats extending from such 95 posts to a longitudinal aisle which is nearer to the closed side of the car than to such posts. 100
- 35 10. A car having one side permanently closed, seating means extending longitudinally along such side, a longitudinal aisle in front thereof, the opposite side of the car having vertical posts between which there are adapted to be open spaces, cross seats extending from such aisle to such posts, and means for closing the openings between the posts, which means are adapted to be raised into the space beneath the roof of the car over such openings. 110
- 40 11. In a street car, the combination of a body permanently closed at one side and adapted to have openings at the other side, a longitudinal aisle nearer the closed side, longitudinal seating means between such aisle and such closed side, a door at the rear end of such aisle, cross seats extending from such aisle to the open side of the car, posts opposite the ends of the seats at such open side, and individual means between said posts for closing such open side, said individual means being adapted to be carried when not in use above the entrance openings and being adapted to be drawn down between the posts to the floor. 60
- 45 12. A car having one side permanently closed and the other side adapted to be opened, longitudinal seating means extending along said closed side, a longitudinal aisle in front of said seating means and nearer said permanently closed side than the other side, and cross seats between such aisle and the open side of the car, said longitudinal seating means extending opposite both the ends of the cross seats and the cross aisle spaces between the cross seats. 70
- 50 13. In a street car, the combination of one permanently closed side a longitudinal aisle nearer such side than the other and having a doorway at its rear end, longitudinal seating means between said aisle and permanently closed side of the car and transverse seats between said aisle and the other side of the car, said longitudinal seating means having seats opposite the spaces between the transverse seats, said other side of the car having upright posts and removable means coöperating therewith. 75
- 55 14. In a convertible car having a permanently closed side, a running board along the opposite side of the car, longitudinally extending seating means upon the closed side, a longitudinally disposed aisle in front of the same, transversely disposed seats extending from the aisle to the other side of the car, said latter side having posts, means for closing the openings between the posts, and a doorway with a door at the end of said aisle. 80
- 60 15. In a convertible car, the combination of one permanently closed side, seating means extending longitudinally along said side, a longitudinal aisle directly in front of the same, transversely disposed seats extending from the aisle to the other side of the car, and means for closing the last mentioned side of the car. 95
- 65 16. In a convertible car, the combination of a permanently closed side, a long bench within the car running from end to end of it and extending along said permanently closed side, a longitudinal aisle directly in front of said bench, transversely disposed seats extending from the aisle to the other side of the car, and means for closing the last mentioned side of the car. 100
- 70 17. In a convertible car, the combination of one open side and one permanently closed side, a bench running from end to end of the car along said permanently closed side with a back toward said side, a longitudinal aisle directly in front of said bench, and transversely disposed seats extending from said aisle to the open side of the car. 110
